UNITED STATES PATENT OFFICE.

ALBERT JOSSELYN, OF PEMBROKE, MASSACHUSETTS.

IMPROVED WINDOW-SCREEN.

Specification forming part of Letters Patent No. 43,855, dated August 16, 1864.

To all whom it may concern:

Be it known that I, ALBERT JOSSELYN, of Pembroke, in the county of Plymouth and State of Massachusetts, have invented a new and Improved Mosquito-Screen, adjustable to windows of various widths; and the following description, with the accompanying drawings, forms a full, clear, and exact specification thereof.

Similar letters represent similar parts in all the views.

Figure 1 is an inside view of the window and screen. Fig. 2 is a horizontal section on line A B of Fig. 1. Fig. 3 is a horizontal section on line C D of Fig. 1.

a represents the window-sash; *b*, the inner head; *c*, the screen of millinett or other suitable fabric.

d is a stile of wood, to which the left-hand side of the screen is secured. This stile is fastened to the window-jamb at the bottom by means of the stud *e* and pin *f*, and at the top by the hook *g*. The right-hand side of the screen is secured to the roller *h*, which, together with the idle-roller *i*, is set in the metallic frame or stock *j*. This metallic stock *j* is secured to the window jamb at the bottom by means of a slot and pin at *k*, and at the top by the hook *l*. The office of the idle roller *i* is to keep the screen closely fitting to the

window-sash, to prevent the ingress of vermin, notwithstanding any amount of cloth may be wound on the roller *h*, which could not be accomplished with a single roller without binding. Another advantage is that the window-sash slides freely independent of the screen. After the sides are fastened to the window-jambs the screen is adjusted to the width by the crank *m*, and held at the required tension by the ratchet-wheel *n*, the pawl *o*, and spring *p*, all of which clearly appears by the drawings. When the season of vermin is over, the screens can be taken down, rolled up, and laid away, and occupy much less room than the ordinary frames, in addition to the advantages before mentioned of adaptation to openings of various widths.

Having thus described my improvement, I claim—

The combination and arrangement of the screen *c*, the stile *d*, the stock *j*, the rollers *h* and *i*, and the ratchet-wheel *n* and the pawl *o*, as an improved mosquito screen, adapted and adjustable to windows of various widths, substantially as set forth and described.

ALBERT JOSSELYN.
